(57) **CLAIM**

The ornamental design for a bottle, as shown and described.

DESCRIPTION

FIG. 1 is a perspective view of a first embodiment of a bottle showing my new design;

FIG. 2 is a front view thereof;

FIG. 3 is a right side view thereof, the left side view being a mirror image thereof;

FIG. 4 is a rear view thereof;

FIG. 5 is a top view thereof;

FIG. 6 is a bottom view thereof;

FIG. 7 is a perspective view of a second embodiment of a bottle showing my new design;

FIG. 8 is a front view thereof;

FIG. 9 is a right side view thereof, the left side view being a mirror image thereof;

FIG. 10 is a rear view thereof;

FIG. 11 is a top view thereof;

FIG. 12 is a bottom view thereof;

FIG. 13 is a perspective view of a first embodiment of a bottle showing my new design;

FIG. 14 is a front view thereof;

FIG. 15 is a right side view thereof, the left side view being a mirror image thereof;

FIG. 16 is a rear view thereof;

FIG. 17 is a top view thereof; and,

FIG. 18 is a bottom view thereof.

The broken lines showing a threaded neck appearing in FIGS. 1-5, 7-11, and 13-17; the broken lines in a central section of the grip shown in FIGS. 1, 2, and 5; and the broken lines showing a grip portion in FIGS. 7-9 and 11; define the bounds of the claimed design and/or disclose the environment related to the claimed design, and therefore form no part of the claimed design. The stippling appearing in the drawings is provided to show shading and does not represent any particular material, color, pattern texture, or surface.
